UNITED STATES PATENT OFFICE.

HENRY JOHNSON, OF ARLINGTON, NEW JERSEY.

DESIGN FOR A PILLAR FOR SIGNAL-STANDS.

SPECIFICATION forming part of Design No. 29,503, dated October 18, 1898.

Application filed September 15, 1898. Serial No. 691,048. Term of patent 14 years.

To all whom it may concern:

Be it known that I, HENRY JOHNSON, a citizen of the United States, and a resident of Arlington, in the county of Hudson and State

5 of New Jersey, have invented and produced a new and original Design for a Pillar for Signal-Stands, of which the following is a specification, reference being had to the accompanying drawings, forming a part thereof.

10 The leading features of my design consist in a pillar for signal-stands having a general T shape in side elevation, a general I shape in edge elevation, and in top plan having the central portion extended laterally in opposite 15 directions from a central line and having portions spaced from the centrally-extended portion, which portions are also laterally extended from the central line.

In the accompanying drawings, Figure 1 represents the pillar in side elevation. Fig. 20 2 represents an edge view, and Fig. 3 a top plan view.

A represents the stem portion, B the head portion, and C the base portion.

What I claim is—

25 The design for a pillar for signal-stands, substantially as shown and described.

In testimony that I claim the foregoing as my invention I have signed my name, in presence of two witnesses, this 16th day of April, 30 1898.

HENRY JOHNSON.

Witnesses:

FREDK. HAYNES,
EDWARD VIESER.
